UNITED STATES PATENT OFFICE.

EDWIN A. OLLEY, OF SYRACUSE, NEW YORK, ASSIGNOR TO CROUSE-HINDS COMPANY,
OF SYRACUSE, NEW YORK, A CORPORATION OF NEW YORK.

PANEL-BOARD CONSTRUCTION.

1,308,607.

Specification of Letters Patent.

Patented July 1, 1919.

Application filed August 2, 1915. Serial No. 43,122.

To all whom it may concern:

Be it known that I, EDWIN A. OLLEY, a citizen of the United States, residing at Syracuse, in the county of Onondaga and 5 State of New York, have invented a certain new and useful Panel-Board Construction, of which the following is a specification.

This invention relates to panel boards, and has for its object a particularly simple panel 10 board construction by which the width of the board is reduced to a minimum; and it consists in the combinations and constructions hereinafter set forth and claimed. Other objects will appear throughout the 15 specification.

In describing this invention, reference is had to the accompanying drawings, in which like characters designate corresponding parts in all the views.

20 Figure 1 is a plan view of the panel board, the electrical appliance forming part of this invention, being removed.

Fig. 2 is a sectional view, partly in elevation, of the electrical appliance omitted in 25 Fig. 1, the base and the bus bars of the panel board being also shown partly in section.

Fig. 3 is a fragmentary detail view, showing in plan a portion of the body of the electrical appliance in full, and also showing in 30 plan a portion of the mechanism within the body of the electrical appliance, parts of said mechanism being removed, the underlying bus bars being also shown.

Fig. 4 is an inverted plan view of the 35 electrical appliance, parts being removed.

The panel board construction comprises, generally, a base, bus bars mounted on the base, an electrical appliance including an insulating body detachably mounted above 40 the bus bars, load circuit controlling devices carried by the body and removable therewith, and also load circuit terminals or bars carried by the body and removable therewith.

45 I have here illustrated my invention as embodied in a panel board for a three wire system.

1 is the base of the panel board, and 2, 3 and 4 are respectively the outside bus bars 50 and the neutral bus bar mounted on the face of the base in parallelism with each other.

55 5 is the insulating body of the electrical appliance. The body is mounted on the base, extends crosswise of the bus bars 2, 3 and 4 and rests at its lower edge on the base, it

having cut-outs 5^a in its lower edge through which the bus bars extend. However, it is not essential that the body 5 rest upon the base of the panel board although it is preferable that it be so arranged.

The load circuit controlling devices are the usual switches and fuse supports, and the switches here shown are of the push button type and the fuse supports of the type which receives a plug. As this embodiment 60 of my invention is adapted for a three wire system, there are two pairs of switches or two double switches, and two pairs of fuse receptacles carried by each body 5. The body 5 is here shown in the form of a housing open at its lower side and having fuse sockets 6 on its top, the switches being housed within the body 5.

7 and 8 are the members of the pairs of load circuit bars carried by the body 5 at 75 opposite ends thereof, the bars 7 and 8 of each pair being connected to one of the outside bus bars 2 or 3, and to the neutral bus bar 4 through switches and fuse devices which are connected in series therewith, as 80 will be understood by those skilled in the art.

The mechanism of each switch is supported by a bridge 9 extending crosswise of the body 5 near the lower side of the body, and includes a pair of rocking switch arms 10 and 11 and means for operating the switch arms, as the operating push buttons 10^a. As the operating means is well known it is thought further description is unnecessary, it being only of importance in so far as this 90 invention is concerned, that the push buttons 10^a extend upwardly through the top of the body 5 or to the outside of the body, so as to be operated from the front side of the panel board.

The switch arm 10 of each switch mechanism engages at its opposite ends with contacts 12, 13 and the switch arm 11 with contacts 14, 15. The contacts 12 and 14 are carried by terminals 16 and 17 which are 100 mechanically secured and electrically connected by screws 18 to upwardly extending portions 19 of the load circuit bars 7 and 8. The screws 18 extend through the end wall of the body 5, through the portions 19 lapping the inner face of the said end wall, and into the base flanges of the conductors 16, 17. The contacts 13 and 15 are carried by conductors 20, 21 having arc-shaped portions 105 lapping or lying against the inner face of 110

the body 5 and secured in position as hereinafter described.

The fuse plug receptacle of each pair includes the usual sleeve terminal 22 or 22^a and 5 the central terminal 23 or 24, the sleeve terminals 22, 22^a each having the usual in-turned base flange resting on the bottom of the socket 6 and overlaid by a washer 25. The sleeve terminals are electrically connected to the arc-shaped conductors 20, 21 10 by screws 26 extending through said arc-shaped conductors, holes in the top of the body 5, the in-turned flanges of the sleeves, and into the washers 25. 15 The central terminal 23 of one of these fuse plug receptacles is a screw extending through the top of the body 5, and a depending boss 5^b on the top, and threading into the upper end of a post 28 rising from one 20 of the bus bars 2 or 3. The central terminal 24 of the other fuse plug is a screw extending through the top of the body 5 and a depending boss 5^b and threading into one 25 end of a conductor or bar 29 lying contiguous to the inner face of the top of the body 5, the bar 29 extending across the upper 30 end of a post 30 rising from the neutral bus bar 4 and being connected to said post by a screw 31 located in a hole in the top of the body 5 and extending through a hole in 35 the bar 29 and threading into the upper end of the post 30. This bar 29 is common to two fuse plug receptacles, as the electrical appliance here shown is of double construction and adapted for a three wire system.

The load circuit bars 7 and 8 lap or lie on the upper face of the base 1, and are secured thereto by suitable binding devices for the load circuit wires. Said binding devices as here illustrated consist of screws 32 extending through the base 1 from the rear or lower side thereof and through the bars 7, 8, and binding nuts 33 screwing on the upper ends of the screws. Obviously 45 the electrical appliance is held in position by the screws 23, 24, 31, 32.

In operation when fuse plugs are inserted in the plug receptacles and one of the switches is operated, so that the arms 10 50 and 11 connect the contacts 12, 13 and 14, 15, the current passes from one outside bus bar 2 or 3 through the post 28, central terminal 23, fuse plug to the sleeve terminal 22^a, then to conductor 21 and the contact 15 55 thereof, switch arm 11, contact 14, load circuit bar 8 through the load circuit, load circuit bar 7, switch contact 12, switch arm 10, contact 13, conductor 20, through the sleeve terminal 22 of the other fuse plug receptacle, 60 through the fuse plug and the central terminal 24, bar 29 and post 30 to the neutral bus bar 4.

This panel board construction is particularly advantageous in that all circuit controlling devices and the load circuit bars are 65

removable as a unit, and this unit is so arranged that the width of the panel board is reduced to a minimum compared with other types of panel boards.

What I claim is:—

1. A panel board comprising a base, bus bars mounted on the face of the base, and an electrical appliance including an insulating body detachably mounted on the base over the bus bar, and load circuit bars arranged at an angle to the bus bar and circuit controlling devices of different character supported by the body, substantially as and for the purpose described. 70

2. A panel board comprising a base, bus bars mounted on the face of the base, electrical appliances comprising an insulating body and load circuit bars, switches and fuse devices, electrically connected with the bus bars, said load circuit bars, switches and 85 fuse devices being carried by the said body, and means for detachably securing the load circuit bars to the base, and thereby mechanically securing the electrical appliance to the panel board, substantially as and for 90 the purpose described.

3. A panel board comprising a base, bus bars on the face of the base, an electrical appliance comprising an insulating body, arranged crosswise of the bus bars, and circuit controlling devices carried by the body, load circuit bar sections carried by the body and connected in circuit with said devices, and means for securing said load circuit bar sections to the panel board base, substantially as and for the purpose specified. 95

4. A panel board comprising a base, bus bars on the base, and a unit mounted on the base and the bus bars and comprising an insulating body arranged crosswise of the bus 105 bars, circuit controlling devices carried by the body and load circuit bars carried by the body, means mechanically securing the load circuit bars to the panel board base, and means for mechanically securing the body 110 and electrically connecting terminals of said devices to the bus bars, substantially as and for the purpose set forth.

5. A panel board comprising a base, outside and neutral bus bars mounted on the 115 face of the base, and an electrical appliance including a single insulating body extending crosswise of the bus bars, a pair of load circuit bars at each end of the body, and a set of circuit controlling devices of different character for each pair of the load circuit bars, the devices of each set being connected in series with one pair of load circuit bars and with one outside bus bar and the neutral bus bar, substantially as and for 120 the purpose described.

6. The combination with a panel board base, of an electrical appliance for panel boards comprising a single insulating body mountable upon the panel board base, two 130

sets of load circuit controlling devices carried by the body including switches within the body, and fuse supports on the outside of the body, the devices of each set being connected in series, and a conductor connecting a device of one set with a like device of the other set, substantially as and for the purpose set forth.

7. The combination with a panel board including a base, bus bars on the base, and posts rising from the bus bars; of an electrical appliance including an insulating body mounted above the bus bars and inclosing the posts, circuit controlling devices located respectively within the body and on the outside thereof, the devices being connected in series with said posts, and fastening members extending through parts of said devices into the ends of the posts, substantially as and for the purpose specified.

8. The combination with a panel board comprising a base, bus bars mounted on the base, and posts rising from the bus bars; of an electrical appliance mounted above the bus bars and including an insulating body

inclosing the posts, and circuit controlling devices mounted within the body and on the top thereof, the devices on the top comprising terminals extending through the top, one terminal consisting of a screw threading into the upper end of one of the posts and a conductor secured to the other terminal and to another post, said controlling devices being connected in series, substantially as and for the purpose set forth.

9. A panel board comprising a base, bus bars mounted on the base, an electrical appliance including a single stationary insulating body mounted on the base and extending crosswise of the bus bars, switch mechanism carried by the base and located within said body and having operating parts extending outside of the body and fuse appliances mounted on the top of the base, substantially as and for the purpose specified.

In testimony whereof, I have hereunto signed my name at Syracuse, in the county of Onondaga, and State of New York, this 30th day of July, 1915.

EDWIN A. OLLEY.
